UNITED STATES PATENT OFFICE.

ALEXANDER WINTON, OF CLEVELAND, OHIO.

DESIGN FOR A COMBINED FRAME FOR EXPLOSION-ENGINE AND CONNECTED DYNAMO.

46,387.

Specification for Design.

Patented Sept. 8, 1914.

Application filed June 25, 1914. Serial No. 847,321. Term of patent 14 years.

To all whom it may concern:

Be it known that I, ALEXANDER WINTON, a citizen of the United States, residing at Cleveland, in the county of Cuyahoga and State of Ohio, have invented a new, original, and ornamental Design for a Combined Frame for Explosion-Engine and Connected Dynamo, of which the following is a specification, reference being had therein to the accompanying drawing.

This invention relates to improvements in designs for a combined frame for explosion engine and connected dynamo, and the ac-

companying drawing is a perspective view of the design.

I claim:

The ornamental design for a combined frame for explosion engine and connected dynamo, as shown.

In testimony whereof I hereunto affix my signature in the present of two witnesses.

ALEXANDER WINTON.
